CONVERSION OF HYDROCARBON OILS

Jean Delattre Seguy, Chicago, Ill., assignor to
Universal Oil Products Company, Chicago, Ill.,
a corporation of Delaware

Application April 23, 1934, Serial No. 721,905

3 Claims. (Cl. 196—48)

This invention particularly refers to an improved process and apparatus for the pyrolytic conversion of hydrocarbon oils of a relatively high-boiling nature for the production of high yields of desirable low-boiling products, such as motor fuel of high antiknock value, of the character wherein the intermediate conversion products of the process are separated into selected relatively low-boiling and high-boiling oils each 5 of which are subjected to the independently controlled conversion conditions most suitable for that particular type of oil.

The present invention employs two independently controlled but interdependent and cooperative cracking units, one of which is specially adapted to the conversion of relatively heavy or high-boiling oils at relatively low temperatures and pressure while the other is particularly suitable for the conversion of relatively light or low-boiling oils at higher temperatures and pressures, each unit being operated for the production of maximum yields of light distillate products boiling within the range of motor fuel. The intermediate conversion products heavier than gasoline (reflux condensate) produced in each unit are separated into selected relatively low-boiling and high-boiling fractions, the high-boiling fractions from each unit being supplied for further conversion to the heating coil of the unit specially 10 adapted to the treatment of high-boiling oils while the low-boiling reflux condensate fractions having boiling characteristics similar to kerosene or pressure distillate bottoms from each unit are supplied for further conversion to the heating coil 15 of the unit particularly adapted to the treatment of relatively low-boiling oils.

One specific embodiment of the present invention may comprise subjecting hydrocarbon oil of relatively high-boiling characteristics to conversion temperature at superatmospheric pressure in a heating coil, introducing heated products into an enlarged reaction chamber, also maintained at superatmospheric pressure, wherein the vaporous and non-vaporous residual conversion products 20 separate, subjecting vaporous products from the reaction chamber to fractionation whereby their high-boiling, insufficiently converted components are condensed as primary reflux condensate having boiling range characteristics corresponding to 25 gas oil, subjecting the remaining vaporous products, corresponding to pressure distillate, to further fractionation whereby the lower boiling, insufficiently converted components, comprising pressure distillate bottoms, are condensed as secondary reflux condensate, subjecting the vapor- 30

ous products from the final stage of fractionation, preferably having an end-boiling point corresponding to that of motor fuel, to condensation, recovering the resulting motor fuel, returning the primary reflux condensate, corresponding, for example, to gas oil, to the heating coil for further conversion, subjecting the secondary reflux condensate, such as pressure distillate bottoms, to independently controlled conversion conditions of elevated temperature and superatmospheric pressure, higher than the temperature and pressure conditions to which the higher-boiling oils, comprising the primary reflux condensate, are subjected, in a separate heating coil and communicating reaction chamber, withdrawing the total 10 conversion products, in commingled state, from the reaction chamber and introducing the same into a reduced pressure vaporizing chamber, wherein vaporous conversion products are separated from residual liquid, withdrawing the latter 15 from the system, subjecting the vaporous conversion products of this stage of the system to fractionation, whereby their high-boiling, insufficiently converted components are condensed and separated into primary and secondary reflux 20 condensate, comprising, respectively, materials corresponding to gas oil and materials corresponding to naphtha and/or kerosene, returning said primary reflux condensate to the first mentioned heating coil for further conversion at relatively 25 low temperature and pressure, returning the secondary reflux condensate to said separate heating coil for further conversion under higher temperature and pressure conditions, subjecting the vaporous products from the last mentioned 30 fractionating stage, preferably corresponding to motor fuel, to condensation and collecting the resulting distillate. It is also within the scope of the invention, when desired, to subject residual liquid conversion products from the first mentioned reaction chamber, when such materials are produced in this zone, to flash distillation, the residual liquid remaining unvaporized after such treatment being withdrawn from the system while the evolved flashed vapors are separated into relatively 35 low-boiling and high-boiling components, the latter being returned to the first mentioned heating coil for further conversion and the former supplied for further conversion to said separate heating coil.

Raw oil charging stock of relatively high-boiling characteristics may be supplied to the heating coil of the cracking unit devoted to the treatment of relatively high-boiling oils or to any suitable intermediate point in the system wherefrom it 40

may be returned to this heating coil. Charging stock of a relatively low-boiling nature may be supplied to the heating coil of the cracking unit devoted to the treatment of relatively low-boiling 5 oils or to any suitable intermediate point in the system wherefrom it may be returned to this heating coil. When a charging stock of relatively wide boiling range is employed it is preferably supplied to a suitable intermediate point or 10 points in either or both of the cracking units wherein it may be separated into selected relatively low-boiling fractions, such as kerosene or naphtha, for example, and high-boiling fractions which are returned, respectively, to the heating 15 coil devoted to the conversion of these fractions, as above described.

The accompanying diagrammatic drawing illustrates one specific form of apparatus embodying the features of the present invention. 20 Referring to the drawing, heating coil 1 is located within a furnace 2 of any suitable form by means of which the required heat is supplied to the oil passing through the heating coil to bring it to the desired conversion temperature preferably at 25 a substantial superatmospheric pressure. The stream of heated oil is discharged from heating coil 1 through line 3 and valve 4 into reaction chamber 5, which is preferably insulated and maintained at a substantial superatmospheric 30 pressure.

Conversion of the oil continues in the reaction chamber and the total conversion products are withdrawn in commingled state from the lower portion of chamber 5, passing through line 6 and 35 valve 7 into vaporizing chamber 8, which is preferably maintained at a substantially reduced pressure relative to that employed in the reaction chamber. Vapors separate from non-vaporous residual liquid in chamber 8 and the residual liquid 40 remaining unvaporized in this zone is withdrawn therefrom through line 9 and valve 10 to cooling and storage or to any desired further treatment. The vaporous conversion products pass from the upper portion of chamber 8 through 45 line 11 and valve 12 to fractionator 13.

Uncondensed vapors of the desired end-boiling point pass from the upper portion of column 13 through line 15 and valve 16 to further fractionation in column 14. A relatively high-boiling or 50 primary reflux condensate, preferably corresponding in initial boiling point to gas oil, is collected in the lower portion of column 13 and a secondary reflux condensate of relatively low-boiling characteristics, such as kerosene or naphtha, for example is recovered from the lower portion of column 14.

Fractionated vapors of the desired end-boiling point, preferably corresponding to motor fuel, are withdrawn, together with uncondensable gas, 55 from the upper portion of fractionator 14 through line 17 and valve 18, to be subjected to condensation and cooling in condenser 19. The resulting motor fuel and uncondensable gas passes through line 20 and valve 21 to collection and separation in receiver 22. Uncondensable gas may be released from the receiver through line 23 and valve 24. The motor fuel may be withdrawn from the receiver through line 25 and valve 26 to storage or to any desired further 60 treatment.

The relatively low-boiling reflux condensate, corresponding to kerosene or naphtha, for example, is withdrawn from the lower portion of fractionator 14 through line 27 and valve 28 to pump 75 29 by means of which it is returned through line

30 and valve 31 to further conversion in heating coil 1.

Reflux condensate of relatively high-boiling characteristics, corresponding to gas oil, for example, is withdrawn from the lower portion of fractionator 13 through line 32 and valve 33 to pump 34, by means of which it is supplied through line 35, valve 36 and line 53 to further conversion in heating coil 37, wherein it is subjected to lower temperature and pressure conditions than those employed in heating coil 1, by means of heat supplied from a suitable furnace 38, of any suitable form. The stream of heated oil is discharged from heating coil 37, preferably at a substantial superatmospheric pressure, through line 39 and valve 40 into reaction chamber 41.

Chamber 41 is preferably insulated and maintained at a substantial superatmospheric pressure. Conversion of the heated products supplied to the reaction chamber from heating coil 20 31 may continue therein. Chamber 41 may be operated for the production of either liquid residue or coke, the residual product in either case being separated in chamber 41 from the vaporous conversion products. When the process is operated for the production of coke as the residual product of this stage of the operation it may be allowed to accumulate within chamber 41 to be removed therefrom in any suitable well known manner after the operation of the chamber is 30 completed. When desired, a plurality of coking chambers, similar to chamber 41 but not shown in the drawing, may be employed and may be either simultaneously operated or, preferably, are alternately operated, cleaned and prepared 35 for further operation so that the continuity of the operation is independent of the capacity of the coking chamber. When a liquid residual product is produced in chamber 41 it may be withdrawn, for example, from the lower portion 40 of this zone through line 42 and valve 43 to cooling and storage or to any desired further treatment. One method of such further treatment which is within the scope of the present invention will be later more fully described. The vaporous conversion products pass from the upper portion of chamber 41 through line 44 and valve 45 to fractionation in fractionator 46.

Fractionated vapors of the desired end-boiling point, preferably lighter than gas oil, pass from 50 the upper portion of fractionator 46 through line 48 and valve 49 to further fractionation in fractionator 47. A relatively high-boiling or primary reflux condensate, corresponding for example to gas oil, is recovered in fractionator 46 and a relatively low-boiling or secondary reflux condensate, corresponding, for example, to pressure distillate bottoms, is recovered from the remaining fractionated vapors in fractionator 47.

The primary reflux condensate recovered in 60 column 46 may be withdrawn from the lower portion of this zone through line 50 and valve 51 to pump 52 by means of which it is returned through line 53 and valve 54 to further conversion in heating coil 37, together with primary 65 reflux condensate from fractionator 13, supplied to this zone as already described.

The secondary reflux condensate formed in fractionator 47 may be withdrawn from the lower portion of the column through line 55 and valve 56 to pump 57 by means of which it is supplied, in the case illustrated, through line 58, valve 59, line 60 and valve 61 to fractionator 13, to serve as a cooling and refluxing medium in this zone to assist fractionation of the vapors by directly com- 75

mingling therewith. The secondary reflux condensate from fractionator 47, thus supplied to fractionator 13, is subjected to vaporization in this zone by direct contact with the relatively

5 hot vapors undergoing fractionation and passes with the uncondensed vapors from column 13 through line 15 and valve 16 to further fractionation in fractionator 14 wherein it is condensed with the secondary reflux condensate 10 formed in this zone, to be returned therefrom to further conversion in heating coil 1, in the manner previously described. It is, of course, also within the scope of the invention, although not illustrated, to supply a regulated portion or all of 15 the secondary reflux condensate from fractionator 47 direct to heating coil 1.

Fractionated vapors of the desired end-boiling point, preferably corresponding to motor fuel, are withdrawn, together with uncondensable gas, 20 from the upper portion of fractionator 47 through line 62 and valve 63 to be subjected to condensation and cooling in condenser 64. The resulting distillate and gas passes through line 65 and valve 66 to collection and separation in receiver 25 67. Uncondensable gas may be released from the receiver through line 68 and valve 69. Distillate may be withdrawn from receiver 67 through line 70 and valve 71 to storage or to any desired further treatment.

30 It is within the scope of the present invention, as previously mentioned, to subject residual liquid conversion products from chamber 41 to further treatment within the system. As an example of one specific method and means of such further treatment, which is within the scope of the invention, all or a regulated portion of the liquid residue from chamber 41 may be diverted from line 42 through line 72 and valve 73 into flash distilling chamber 74, which is operated at a substantially reduced pressure relative to that employed in chamber 41, by means of which appreciable further vaporization of the residual liquid is accomplished. The residual liquid remaining unvaporized in chamber 74 may be withdrawn therefrom through line 75 and valve 76 to cooling and storage or elsewhere, as desired. The vapors evolved in chamber 74 pass, in the case illustrated, from the upper portion thereof through line 77 and valve 78 to fractionation in 45 fractionator 79.

50 The components of the vaporous products supplied to fractionator 79, approximately corresponding in boiling characteristics to the primary reflux condensate recovered in fractionators 13 and 46, are condensed as flash condensate. This material may be withdrawn from the lower portion of column 79 through line 80 and valve 81 to pump 82, wherefrom it is fed through line 83 to be returned to heating coil 37 for further conversion, being supplied, in the case illustrated, either through valve 84 in line 83 and through line 53 direct to heating coil 37 or from line 83 through line 85 and valve 86 into fractionator 46, to serve as a cooling and refluxing medium and to be returned therefrom, together with the reflux condensate formed in this zone, to heating coil 37, in the manner previously described.

55 The components of the vapors evolved in chamber 74 remaining uncondensed in fractionator 79, including, primarily, materials boiling within the range of the secondary reflux condensate formed in fractionators 14 and 47, as well as any lower boiling materials, are withdrawn, together with uncondensable gas, from the upper portion of 60 fractionator 79 through line 87 and valve 88 to be

subjected to condensation and cooling in condenser 89, wherefrom the resulting distillate and gas passes through line 90 and valve 91 to collection and separation in receiver 92. Uncondensable gas may be released from the receiver through line 93 and valve 94. All or a regulated portion of the distillate may be withdrawn from receiver 92 through line 95 and valve 96 to storage or elsewhere, as desired. Preferably, however, all or a regulated portion of the distillate collected in receiver 92 is withdrawn therefrom through line 97 and valve 98 to pump 99, by means of which it is fed, in the case illustrated, through line 100, valve 101, line 60 and valve 61 into fractionator 13, together with the secondary reflux condensate from fractionator 47. It is also within the scope of the present invention, particularly in case the flash distillate collected in receiver 92 comprises or contains a substantial proportion of materials within the boiling range of motor fuel but of poor antiknock value, to return the distillate from receiver 92, by well known means, not illustrated, direct to heating coil 1, whereby the characteristics of the motor fuel components of the distillate may be materially improved, particularly with respect to their antiknock value, under the conversion conditions employed in this zone.

When a hydrocarbon oil charging stock of relatively high-boiling characteristics or of relatively wide boiling range is employed it may be supplied through line 102 and valve 103 to pump 104 wherefrom it is fed through line 105 and may be directed, all or in part, either through line 106 and valve 107 into fractionator 79 or through line 108, line 109, valve 110 and line 72 into flash distilling chamber 74, or from line 108 through line 111 and valve 112 into the lower portion of reaction chamber 41. It is also within the scope of the invention, although not illustrated in the drawing, to supply charging stock of relatively high-boiling characteristics or charging stock of relatively wide boiling range either to fractionator 13 or to chamber 8 or to the lower portion of chamber 5, or the charging stock supplied to pump 104 may be fed to the system in any desired combination of the manners described. Charging stock of relatively high-boiling characteristics may also, when desired, be fed from pump 104 through lines 105, 108 and valve 113 direct to heating coil 37.

When charging stock of relatively low-boiling characteristics is employed it may be supplied through line 114 and valve 115 to pump 116 to be fed therefrom through line 117 and supplied, all or in part, either through line 118 and valve 119 to fractionator 14 or through line 120, valve 121 and line 60 to fractionator 13, or relatively low-boiling charging stock may be supplied, by well known means, not illustrated, either to fractionator 46 or to fractionator 47 or to fractionator 79, or it may be supplied to the system in any combination of the manners described.

It is, of course, within the scope of the invention to employ both low-boiling and high-boiling charging stocks or to employ either or both in combination with a charging stock of relatively wide boiling range, although means for supplying more than two charging stocks to the system separately are not illustrated.

70 It will be understood that the invention is not limited to the specific form of apparatus illustrated and above described nor to the specific flow shown. As an example of some of the many modifications possible within the scope of the 75

present invention, a single fractionator may be employed instead of employing two fractionators in series such as fractionators 13 and 14 and/or fractionators 46 and 47, in which case high-boiling fractions of the reflux condensate may be withdrawn from the lower portion of the fractionator, to be returned to heating coil 37, while selected low-boiling fractions of the reflux condensate are withdrawn from any suitable intermediate point or plurality of points in the fractionator, to be returned to heating coil 1 for further conversion. Preferably a light distillate product of motor fuel boiling range is separately recovered from each of the two separate cracking stages of the system, since the cracking unit devoted to the treatment of relatively low-boiling oils will ordinarily produce a product superior in motor fuel characteristics, particularly with respect to its antiknock value, as compared with the motor fuel produced in the cracking unit devoted to the treatment of the relatively high-boiling oils, and it may be undesirable to blend the two motor fuel products. When flash distillation of the residual liquid from chamber 41 is desired and it is not objectionable to blend the residual liquid products from the two cracking stages of the system, the residual liquid from chamber 41 may be directed to vaporizing chamber 8, thus eliminating flash distilling chamber 14 and the communicating fractionating, condensing and collecting equipment.

Preferred operating conditions of an apparatus such as illustrated and above described may be approximately as follows: The heating coil to which the relatively low-boiling oils are supplied may utilize an outlet conversion temperature of from 900 to 1050° F., or thereabouts, preferably with a substantial superatmospheric pressure, measured at this point in the system, of from 200 to 1000 pounds, or thereabouts, per sq. in. Substantially the same or a somewhat reduced superatmospheric pressure may be employed in the succeeding reaction chamber but is preferably reduced in the vaporizing chamber to a pressure of the order of 100 pounds, or thereabouts, to substantially atmospheric pressure. The pressures employed in the fractionating, condensing and collecting portions of the light oil cracking stage may be substantially the same or somewhat lower than the pressure employed in the vaporizing chamber. The heating coil wherein the relatively high-boiling oils are subjected to conversion may utilize an outlet temperature of the order of 800 to 950° F., preferably with a superatmospheric pressure, measured at the outlet from the heating coil, of from 100 to 500 pounds, or thereabouts, per sq. in. Substantially the same or somewhat lower pressures may be employed in the succeeding reaction chamber and may be either substantially equalized or reduced appreciably in the succeeding fractionating, condensing and collecting portions of the heavy oil cracking stage. When a separate flash distilling system is utilized for the residual liquid from the reaction chamber of the heavy oil cracking stage the flash distilling chamber employs a substantially reduced pressure relative to that employed in the reaction chamber, which may range, for example, from 100 pounds, or thereabouts, per sq. in., down to substantially atmospheric pressure. The pressure employed in the flash distilling chamber may be either substantially equalized or somewhat reduced in the succeeding fractionating, condensing and collecting equipment.

75 As a specific example of one of the many pos-

sible operations of the process of the present invention as it may be practiced in an apparatus such as illustrated and above described; the charging stock is a Mid-Continent fuel oil of about 23° A. P. I. gravity which is supplied, together with high-boiling or primary reflux condensates from both cracking stages of the system, to the heating coil of the heavy oil cracking stage, wherein they are subjected to an outlet conversion temperature of approximately 930° F. and a superatmospheric pressure of approximately 300 pounds per sq. in. Substantially the same pressure is employed in the succeeding reaction chamber wherein the residual conversion products are reduced to coke. The low-boiling fractions of the reflux condensate from both cracking stages of the system, which has a boiling range of approximately 390 to 560° F., comprises the oil supplied to the heating coil of the light oil cracking stage, wherein it is subjected to an outlet conversion temperature of approximately 975° F. at a superatmospheric pressure of about 800 pounds per sq. in. Substantially the same pressure is employed in the reaction chamber but is reduced in the succeeding vaporizing chamber to a pressure of approximately 60 pounds per sq. in. This operation may yield, per barrel of charging stock, a total of approximately 59 percent of motor fuel of good antiknock value, approximately 100 pounds of coke, about 5 percent of heavy liquid residue and about 600 cubic feet of rich uncondensable gas.

In an operation similar to that above described except that a separate low-boiling charging stock comprising a Pennsylvania distillate of about 42° A. P. I. gravity, approximately equivalent in volume to the heavy charging stock, is subjected to conversion in the light oil cracking stage, there may be produced, per barrel of total charging stock, about 65 percent of total motor fuel having an antiknock value equivalent to an octane number of approximately 70, about 60 pounds of coke, about 7.5 percent of heavy residual liquid suitable for use as fuel and approximately 700 cubic feet of rich uncondensable gas.

I claim as my invention:

1. A conversion process which comprises cracking hydrocarbon oil under pressure in a cracking zone, removing vapors and unvaporized oil from said zone, subjecting the vapors to primary and secondary fractionation, returning resultant primary reflux condensate to said cracking zone, cracking lighter fractions condensed by the secondary fractionation in a second cracking zone at higher temperature than the oil in the first-named zone, separating the resultant products into vapors and residue in a reduced pressure separating chamber, fractionating the last-mentioned vapors and separating relatively heavy and light reflux condensates therefrom, supplying the heavy and light reflux condensates thus formed respectively to the first-named zone and said second zone, introducing unvaporized oil withdrawn from the first-named zone into a second reduced pressure chamber and therein flash distilling the same independently of said products from the second cracking zone, introducing charging oil for the process to said second chamber and distilling the same therein, removing the commingled charging oil vapors and flashed vapors from the second chamber and fractionally condensing the same to form a heavy condensate and a lighter condensate, and supplying these heavy and lighter condensates respectively to the 75

first-named cracking zone and said second cracking zone.

2. A hydrocarbon oil conversion process which comprises cracking a relatively heavy oil in a first cracking zone, simultaneously cracking a lighter oil at higher temperature in a second cracking zone, removing vapors from said second zone and subjecting the same to primary fractionation in a primary fractionator and then to secondary fractionation in a secondary fractionator, returning reflux condensate from said secondary fractionator to the second cracking zone, removing vapors from said first zone and subjecting the same to primary and secondary fractionation independently of the first-mentioned vapors, returning reflux condensate formed by the last-mentioned primary fractionation to said first zone, introducing reflux condensate formed by the last-mentioned secondary fractionation into said primary fractionator and into contact with the vapors undergoing fractionation therein, supplying reflux condensate from said primary fractionator to said first cracking zone, withdrawing cracked unvaporized oil from said first cracking zone and flash distilling the same by pressure reduction, fractionally condensing the flashed vapors to form a relatively heavy condensate and a lighter condensate, introducing the lighter condensate into said primary fractionator and introducing the heavy condensate into contact with the vapors from the first cracking zone during

the independent primary fractionation thereof, and finally condensing and collecting fractionated vapors.

3. A hydrocarbon oil conversion process which comprises cracking a relatively heavy oil in a first cracking zone, simultaneously cracking a lighter oil at higher temperature in a second cracking zone, removing vapors from said first zone and subjecting the same to primary fractionation in a primary fractionator, removing vapors from said second zone and subjecting the same to primary fractionation in an independent primary fractionator, further fractionating the vapors uncondensed in said fractionators and supplying resultant reflux condensate to said second zone, removing cracked unvaporized oil from said first zone and flash distilling the same by pressure reduction, fractionally condensing the resultant flashed vapors to form a relatively heavy condensate and a lighter condensate, introducing the heavy condensate into the first-mentioned fractionator and the lighter condensate into said independent fractionator, supplying reflux condensate from the first-mentioned fractionator and from said independent fractionator to the first cracking zone, and finally condensing the vapors uncondensed by the further fractionation of the vapors from said primary fractionators.

JEAN DELATTRE SEGUY. 30
